United States Patent

Des. 235,314
Patented June 10, 1975

235,314

CARTON

Ronald Frederick Cramphorn, Marlow, England, assignor
to Aspro Nicholas, Ltd., Slough, England

Filed Dec. 14, 1971, Ser. No. 208,052

Claims priority, application Great Britain June 26, 1971

Term of patent 14 years

Int. Cl. D9—03

U.S. Cl. D9—222

FIG.1.

FIG.2.

FIG. 3.

FIG. 5.

FIG. 4.

FIG. 1 is a front perspective view of a carton, showing my new design;

FIG. 2 is a rear elevational view;

FIG. 3 is a side elevational view;

FIG. 4 is an underneath plan view;

FIG. 5 is a top plan view;

My design is characterized by an elongated box having two closed ends, one of which is a parallelogram in plan which merges along the box sides into the other end which is a concave ellipse.

I claim:

The ornamental design for a carton, as shown and described.
